UNITED STATES PATENT OFFICE.

WILLIAM H. DOANE AND GEORGE W. BUGBEE, OF CINCINNATI, OHIO.

SPOKE TENONING AND THROATING MACHINE.

SPECIFICATION forming part of Letters Patent No. 276,009, dated April 17, 1883.

Application filed January 15, 1883. (No model.)

To all whom it may concern:

Be it known that we, WILLIAM H. DOANE and GEORGE W. BUGBEE, citizens of the United States, residing at Cincinnati, in the county of Hamilton and State of Ohio, have invented certain new and useful Improvements in Spoke Tenoners and Throaters; and we do hereby declare the following to be a full, clear, and exact description of the invention, such as will enable others skilled in the art to which it appertains to make and use the same.

This invention consists of a machine adapted to both tenon and throat spokes during one and the same passage, or to either tenon or throat them, at the pleasure of the user, by feeding such spokes by an endless articulated bed or other feeding mechanism through, between, or past suitable cutter-heads.

The novel features of construction and the novel combinations embodied in the machine are set forth in the claims at the close of this specification.

In order that the invention may be clearly understood, we have illustrated in the annexed drawings and will proceed to describe the best form of the combined machine at present known to us.

Figure 1 is a plan view of the machine. Figs. 2 and 2^a illustrate a front elevation of the same. Fig. 3 is a side elevation thereof. Figs. 4 to 6 illustrate details of the machine.

The same letters of reference indicate identical parts in all the figures.

The main frame of the machine consists of a hollow column, A, constructed with suitable wings for the support respectively of the standard A', on which the slides of the tenoning cutter-heads are mounted, and the housings A² of the articulated endless traveling bed. The front face of standard A' is provided with parallel vertical ways, on which the slides B' and C' are fitted. These slides are connected by a screw, C², which is swiveled to one and engages a nut on the other, so that by turning the screw by the hand-wheel C³, secured thereto, the slide provided with the nut may be adjusted with reference to the other slide. In this instance the lower slide, C', is provided with the nut for screw C². The upper slide, B', is also provided with a nut, which is engaged by a screw, B², which extends upward and is swiveled to a bracket

on standard A', carrying at its upper end a hand-wheel, B³. By turning screw B² by its hand-wheel both slides B' and C' may be simultaneously adjusted. A horizontal shaft, B⁴, is journaled in suitable bearings of slide B', carrying at its inner end the upper tenoning cutter-head, B, and at its outer end a pulley, B⁵, by which it is driven. A similar horizontal shaft, C⁴, is journaled in suitable bearings of slide C', carrying at its inner end the lower tenoning cutter-head, C, and at its outer end a pulley, C⁵, by which it is driven. The tenoning cutter-heads may be of any preferred construction, and armed with suitable cutters in the ordinary way. The pulleys B⁵ and C⁵, arranged in line, are driven by a single belt, E², from a pulley, E', on the shaft E of the machine, in the manner clearly shown in Fig. 70, the belt being kept at proper tension under all adjustments of the slides B' and C' by a tightener-pulley, E³, journaled on a stud projecting laterally from the short arm of a lever, E⁴, which is fulcrumed on standard A', 75 and carries an adjustable weight on its long arm.

In order to prevent vibration and endwise movement of the spoke during its passage through between the tenoning cutter-heads, 80 holders are provided, the lower one of which is unyielding and bears on the lower side of the spoke, while the upper one, which bears on the upper side of the spoke, is yielding. These holders extend across the ends of the 85 respective cutter-heads in close proximity thereto, (see Figs. 1 and 2,) so that they will bear on the spoke close to the shoulder of the tenon to be cut thereon. The lower holder, F, is a straight steel bar set up edgewise and 90 firmly held in a groove in the top of a bracket, F', which projects from slide C', to which it is so fitted as to be vertically adjustable thereon, in order that holder F may be set at the proper elevation with respect to cutter-head C. The top edge of holder F projects a little above its supporting-yoke, and has a dull edge, so that it may make a slight indentation in the spoke before reaching the cutter-heads and thus compel the spoke to continue its advance without endwise deviation. The upper holder, G, is a flat bar arranged edgewise in a slot in the lower edge of a yoke, G', which projects from slide B', and is so fitted thereto

that it may be vertically adjusted thereon for suspending holder G at the proper height with respect to cutter-head B. Holder G is provided with vertical slots, through which pass pins secured in the yoke to prevent the falling of the holder from its seat in the yoke. Near each end of holder G a pocket is formed above it in the yoke for the reception of a spiral or rubber spring, by means of which the holder 5 is pressed downward to act with a yielding pressure on the top of the spoke. The length of the tenon to be cut is determined by the gage F², fitted on the forward end bracket, F', and adjustable crosswise thereon.

10 The throating cutter-heads are located some little distance to the rear of the tenoning cutter-heads and project beyond the outer ends thereof. Thus a spoke may be fed by the same endless traveling bed from the tenoning 15 cutter-heads to and through between the throating cutter-heads and throated at the proper point. The lower throating cutter-head, H, is arranged so far in advance of the upper one, I, that they may swing past each other far enough to throat the spoke to a sharp edge, if desired. The cutter-head H is 20 fixed to the inner end of a shaft, H', journaled in suitable bearings of a hanger, H², and carrying at its outer end a rim-pulley, H³. The hanger H² is pivoted on a stud, h, projecting 25 horizontally from the front side of a slide, H⁴, gibbed to a vertical rail on an offset formed on the front side of the column A of the main frame. Slide H⁴ is provided with a nut which 30 is engaged by the screw-threaded upper end of a downwardly-projecting screw swiveled to the main frame and provided at its lower end with a suitable hand-wheel for turning it. Cutter-head I is fixed to the inner end of a 35 shaft, I', journaled in suitable bearings of a hanger, I², and carrying at its outer end a rim-pulley, I³. Shaft H' is longer than shaft I' in order that the pulleys H³ and I³ may be located in different vertical planes to prevent 40 interference of the belts by which they are driven. Hanger I² is pivoted on a stud, i, projecting horizontally from the front side of a slide, I⁴, gibbed to a vertical rail on the front side of upper end of column A. Slide I⁴ is provided with a nut on its back, which is 45 engaged by the screw-threaded lower end of a screw, I⁵, which is swiveled to the top plate of the column A, and at its upper end provided with a hand-wheel, I⁶, for turning it. The slides H⁴ and I⁴ may thus be adjusted up 50 and down by turning the screws. The nut and screw of slide H⁴ are omitted from the drawings for the sake of avoiding complexity; but any one skilled in the art can readily apply them from the description given.

55 Pulley H³ is driven by an open or straight belt, H⁵, and pulley I³ by a crossed belt, I⁷, from pulleys on a counter-shaft, (not shown,) but arranged in a plane about midway between the cutter-head shafts H' and I'. Another pulley on the same counter-shaft drives a pulley, E⁸, keyed to shaft E by a crossed belt,

E⁶. The hanger H² is so hung that its cutter-head has a constant tendency to move upward, while hanger I² is so hung that its cutter-head 70 has a constant tendency to move downward, and the action of the belts H⁵ and I⁷ furthers these tendencies. The hangers may be provided with adjustable weights for convenience of balancing the downward pressure of one 75 cutter-head by the upward pressure of the other. The respective frames of the hangers H² and I² are extended behind their cutter-heads to reach beyond the outer ends thereof. To each of these extensions a horizontally-adjustable bracket (marked h' and i', respectively) is fitted, projecting across the ends of the respective cutter-heads H and I. To bracket h' is secured a vertically-adjustable bar, h², of horseshoe form, projecting upward 80 from said bracket, and a similar vertically-adjustable bar, i², is secured to bracket i, projecting downward therefrom. They act as directors, determining the lines of the cuts of the cutter-heads H and I by following the 85 cross-sectional contour of every spoke fed past or across their closed curved ends.

In order that the tenoned end of the spoke 90 may be supported during the action of the throating cutter-heads, guides K and K' are provided behind the rear ends of said cutter-heads, 95 extending from near the tenoning cutter-heads to past the center of the throating cutter-head I. The lower guide, K', is fitted to slide in a horizontal guideway in the top of the step of 100 column A, and is adjusted by a screw, k', in directions parallel to the axis of the throating cutter-heads. The upper guide, K, is fitted in an upright knee of the lower guide, and is adjusted vertically by a screw, k. By proper adjustments by means of screws k and k' these tenon-guides may be adjusted to the length and thickness of the tenons.

The articulated endless traveling bed for 110 feeding the spokes through the machine consists of a pair of endless chains, L L, and a series of cross-slats, L', secured to said endless chains, and provided with suitable fingers for holding the spokes. The endless chains are passed around flanged wheels on a shaft, L², 115 at the front end of housing A², and around sprocket-wheels on a shaft, L³, at the rear end of said housing. Shaft L³ is journaled in fixed bearings, while shaft L² is journaled in horizontally-adjustable bearings, by adjusting 120 which the chains L L may be properly stretched. Shaft L³ is driven at the proper speed by a train of spur-wheels from a shaft, M, which is in turn driven by a cone friction-clutch. The female cone, M', thereof, which is also a pulley, 125 turns loosely on shaft M, and is driven by a belt from a pulley on the same counter-shaft which drives the throating cutter-heads. The male cone, M², thereof is feathered to shaft M, so that it may be slid thereon, and is constructed with a circular groove in its hub, 130 which is engaged by the forked end of a shifter-rod, M³, pivoted at its other end to lever M⁴, which is fulcrumed on the main frame, and

constructed with a handle which reaches to the front end of the traveling bed, where the operator stands in supplying it with spokes. The top edges of the sides of housing A² form 5 parallel horizontal rails for the support of the ends of slats L'. At each end each slat L' is provided with a pair of fingers, l l', which project at right angles from the face of the slat, and are formed on the reverse ends of arms 10 fitted side by side in a dovetailed groove across the slat. In order that these fingers may be firmly held in place, and also readily adjusted with reference to each other as well as with reference to the slat, they are secured by 15 crowding them against each other toward one edge of the dovetailed groove of the slat by a screw, l², the tapering head of which may act directly on the beveled edge of one of the fingers, or which may operate a wedging cap, l³, 20 as shown.

A presser-bar, N, is provided for holding the spokes down on the slats of the traveling bed. The shank of this presser-bar is curved, as shown in Fig. 1, and fitted on a vertical 25 dovetailed rail on the side of column A, a screw, N', swiveled to a lug on said shank and screwing into a nut on the column, being employed to hold the presser-bar at any required elevation above the traveling bed. A deep groove 30 is formed in the lower edge of this presser-bar for the accommodation of a series of yielding pressers, n, which are suspended at each end from pins fixed in the presser-bar and passing through vertical slots in the pressers n. Spiral or rubber springs are inserted in pockets 35 of presser-bar above the presser, near their ends, which force the pressers with yielding pressure down upon the spokes. The adjacent ends of every two pressers are lap-jointed 40 and their lower corners rounded. By virtue of these yielding pressers the presser-bar is enabled to hold down every individual spoke with equal force, since the pressers accommodate themselves to differences in the thickness 45 of the spoke.

In the practical operation of this machine the spokes are fed crosswise in a straight line through between the cutter-heads. In order that the spokes may be tenoned as required to 50 give the proper dish when driven into a wheel-hub, they are fed lying at a slight slant on the traveling endless bed. This slant is determined by adjustment of the fingers l l' at one end of slats L' with reference to the fingers at 55 the other end thereof. As each slat moves up around the flanged wheels of shaft L² at the front end of the machine, the operator places a blank-spoke between the fingers thereof, taking care to run the end to be tenoned and 60 throated up against the gage L². Immediately afterward the spoke passes under presser-bar N and between holders F and G, the presser-bar holding the spoke down from that time until it is discharged, after having been 65 tenoned and throated. After a tenon has been cut on it, its tenoned end passes between the guides K and K', whereby this end is sup-

ported until the throating is finished. The tenoned and throated spokes, on falling from the fingers of the traveling bed at the rear 70 end of the machine, may be received in a rack.

We believe that we are the first to produce a machine adapted to first tenon and then throat a spoke as it is being fed through the machine. In view of this fact we do not propose to confine ourselves primarily to the particular form of our invention illustrated and hereinbefore described in detail, the embodiment of the invention being capable of assuming forms in many respects quite different 80 therefrom. For instance, instead of using a pair of tenoning cutter-heads and a pair of throating cutter-heads, only a single tenoning cutter-head and a single throating cutter-head may be employed, so as to operate on only one 85 side of the spoke at the time. Other means than an endless traveling bed and a presser-bar may be used for feeding the spoke and holding it steady—as, for instance, a reciprocating carriage and presser-rollers. 90

Having thus described our invention, what we claim is—

1. A machine for tenoning and throating spokes at a single pass, characterized by containing a tenoning cutter-head, a yielding 95 throating cutter-head, which projects beyond the tenoning cutter-head, and feed mechanism for conveying the spoke in the specified relation past the cutter-heads, substantially as before set forth. 100

2. The combination, substantially as before set forth, of a pair of tenoning cutter-heads, a pair of yielding throating cutter-heads, which project beyond the tenoning cutter-heads, and feed mechanism for conveying the spokes in 105 the specified relation past the cutter-heads.

3. The combination, substantially as before set forth, of the yielding throating cutter-heads, having the form substantially as shown, and the articulated endless traveling bed, having 110 spoke-clamps, as described.

4. The combination, substantially as before set forth, of the yielding throating cutter-heads, the articulated endless traveling bed, having spoke-holders, as described, and a 115 presser-bar over said bed.

5. The combination, substantially as before set forth, of the tenoning cutter-heads, the spoke-holders associated therewith for holding the spokes at the throat, the guides for the 120 tenon of the spoke, the yielding throating cutter-heads, and feed mechanism for conveying the spokes in the specified relation past the cutter-heads.

6. The combination, substantially as before 125 set forth, of the tenoning cutter-heads, the spoke-holders associated therewith for holding the spokes at the throat, the guides for the tenon of the spoke, the yielding throating cutter-heads, the articulated endless traveling 130 bed, and a presser-bar over said bed.

7. A presser-bar provided with a presser or pressers arranged in a groove in the edge of said bar and bearing against springs therein,

the adjacent ends of the pressers overlapping each other, substantially as before set forth.

8. The combination, substantially as before set forth, of the slats of the articulated endless traveling bed, one pair of adjustable fingers at one end of each slat, and a similar pair of such fingers at the other end thereof.

In testimony whereof we affix our signatures in presence of two witnesses.

WILLIAM HOWARD DOANE.
GEORGE WARREN BUGBEE.
